ARCHIBALD EATON GOLDSPINK, OF KENTISH TOWN, LONDON, ENGLAND, ASSIGNOR TO
CHAPPELL & COMPANY, LIMITED, OF LONDON, ENGLAND.

PNEUMATIC ACTION FOR PIANO-PLAYERS.

1,298,491.

Specification of Letters Patent.

Patented Mar. 25, 1919.

Application filed February 4, 1919. Serial No. 274,944.

To all whom it may concern:

Be it known that I, ARCHIBALD EATON GOLDSPINK, a subject of the King of England, residing at Kentish Town, in London, 5 England, have invented certain new and useful Improvements in Pneumatic Actions for Piano-Players, of which the following is a specification.

This invention relates to pneumatic piano-player actions of the type wherein a wind-trunk or channel board has a series of valve-carrying units detachably secured along one side thereof and connected thereto by passages situated at right-angles to the said side 15 of the wind-trunk, and a corresponding number of bellows for the striker-mechanisms are provided located at right-angles to the wind-trunk, each being controlled by its allotted unit.

20 Heretofore it has been proposed to combine casings containing valves with a bellows to form single detachable units, each valve-casing being securely carried upon its allotted bellows which extend under the wind-trunk; in this arrangement the valve-casing and the diaphragm contained therein for operating one of the valves could not be entirely removed together as one unit without also removing the bellows, and the passage 25 for placing the bellows into communication with atmosphere or with the wind-trunk was situated in the end of the unit away from the wind-trunk, so that the size of each detachable unit was increased by the 30 space occupied at the end of the unit by this passage.

This invention has for its object to provide an improved arrangement of the valve-carrying units in combination with the bellows 40 and wind-trunk, such that each unit can be readily removed in its entirety from the wind-trunk and its allotted bellows without disturbing these or other parts, and such that the air passages shall be reduced in 45 length and have fewer bends. Such units when defective can be readily scrapped and replaced by others.

The invention consists in the construction, arrangement and combination of parts described hereinafter and pointed out in the 50 claims.

One embodiment of the invention is illustrated by way of example in the accompanying drawing wherein:

55 Figure 1 is a transverse sectional eleva-

tion showing one form of improved pneumatic piano-player action comprising a wind-trunk and a valve-carrying unit at one side thereof;

Fig. 2 is a top plan view of the unit alone, 60 and

Fig. 3 is an end elevation of the unit.

Like reference letters designate like parts in all views.

Referring to the drawing, the unit is divided into two principal parts, an upper part comprising three layers A, A² and A³ of wood or other material, and a lower part comprising the oblong block B also of wood or other material. The lower block B has 70 a recess B¹ in its upper face closed by a flexible diaphragm C of usual construction. The unit is mounted on a wind-trunk or channel board D in the manner described 75 hereinafter.

The upper part of the unit is shaped externally to agree with the lower, and is provided in its upper face with a recess E which constitutes the valve-chamber. Its lower face is also recessed at A¹ to register with the recess B¹ in the lower part of the unit, and a passage is pierced in the wall A² between the valve-chamber E and the recess A¹ to admit the body of an air-valve F. The air-valve is 80 of the usual double-beat type, having one 85 seating E¹ upon the lower part of the valve-chamber and another E² which is detachable from the upper face of the valve, is downwardly directed and is secured to the upper face of the upper part of the unit. The valve 90 is guided both at its upper and lower seating. When the valve is upon its lower seat E¹ the valve-chamber E is open to the atmosphere, and when the valve is upon its upper seat E² the chamber E is closed thereto and open to 95 the recess A¹ beneath the valve. A horizontally-situated passage E³ extends from the valve-chamber E to the end face of the upper part of the unit, and a similar passage A⁴ extends from the recess A¹ to the same face of 100 the unit. The two parts constituting the unit are united together by screws, the lower face of the one to the upper face of the other, the joint being made airtight, the margin of the flexible diaphragm C being used as packing material.

The wind-trunk D which carries the units is of hollow rectangular section and extends horizontally along the piano-player. A series of units, one for each note, is bolted along 110

one side of the wind-trunk with their pierced sides abutting against it, and their under faces flush with the under surface of the casing D⁴ of the wind-trunk. When so united 5 the interior of the wind-trunk communicates with the passage A⁴ leading beneath the air-valve, and a passage D² leading from a bellows L of the striking-pneumatic and formed in two adjacent sides of the casing D⁴ of the 10 wind-trunk, communicates with the passage E³ leading to the valve-chamber. An airtight joint is made by means of packing material P at the contact faces of the unit and the wind-trunk. Bolts G (Figs. 2 and 15 3) securing the unit to the wind-trunk extend along the sides of the unit and beyond its outer end, grooves being provided in the sides of each unit so that the shank of each bolt lies partly in one unit and partly in the 20 next one which is in contact with it. The washers and nuts upon the bolts therefore bear partly on one unit and partly upon the next adjacent one.

Leading to the recess B¹ beneath the flexible diaphragm C is a passage B² pierced in the outer end of the lower part of the unit, and adjacent thereto in the end of the layer A³ an air-vent H is provided consisting of a pierced metal plug. As clearly shown, a 25 short channel connects the air-vent with the recess B¹ beneath the diaphragm.

A metal plate J (Fig. 3) having a hemispherical boss J¹ pressed in it is attached by screws to the block B so that the boss J¹ 30 communicates with both the air-vent H and the recess beneath the diaphragm. An upwardly-directed tube K opening into the boss J¹ can be connected by a flexible tube to the tracker-bar.

40 The bellows L of the striking-pneumatic is attached to the underside of the wind-trunk D and extends under, and is in contact with, the lower face of the unit. The member B is not attached to the bellows L 45 by any means.

The action of the above described mechanism is substantially as follows:—In Fig. 1 the normal position of the parts are shown in which atmospheric air has free access 50 through the valve chamber E and through the passages E³ and D² to bellows L.

Whenever a perforation on the paper music sheet is brought into registry with one of the ducts in the tracker board, air 55 will be admitted through the fitting K to the boss J¹ and passage B² to the under side of the diaphragm C. Of course the upper side of the diaphragm is in communication with the exhaust trunk D, and consequently the 60 presence of atmospheric air below the diaphragm C will exert a pressure thereon, driving the same up and moving the valve F up to the upper valve seat E, thus shutting out the atmosphere and placing the 65 valve chamber E and the recess A¹ in com-

munication. The exhaust trunk D will draw the air from the bellows L through the passage D³, causing the bellows to actuate in the usual way. After the perforation on the music roll has passed the duct the atmospheric air will be shut off from the fitting K, and as soon as the trunk D has exhausted the air from the recess A¹, the atmospheric pressure on the top of the valve F will return this valve to the lower seat 75 E¹, and the apparatus will be then in initial position in readiness for the next actuation. The passage H above the passage E permits the escape of the atmospheric air from the chamber beneath the diaphragm C, 80 and it also furnishes a means of communication between the chamber B and the recess A¹, which permits of establishing and maintaining a balance between these chambers, which is desirable for an effective action of 85 the diaphragm C.

It will be seen from the above description that each important part of the action is readily accessible for cleaning, adjustment, repairs or renewal, and also that units so 90 constructed are interchangeable.

It will be apparent that various modifications in the arrangement and details herein described can be made without departing from the spirit of the invention as defined 95 in the claims. The material employed in the construction of the unit may be wood, metal, vulcanite or the like as may be required to suit climatic or other conditions.

What I claim as my invention and desire to secure by Letters Patent is:—

1. In pneumatic piano actions, the combination of a bellows and a wind trunk having an exhaust space with an opening through one side of the trunk communicating with the exhaust space and a right angled passage communicating at one end with said bellows and having its other end opening through the side of the trunk just above said first mentioned opening, a valve 105 carrying unit removably supported on the bellows at the side of said wind trunk, said unit being composed of three superposed layers, each layer being recessed centrally, the recesses in the layers communicating 110 with each other, the recess in the uppermost layer providing a valve chamber, upper and lower valve seats in said chamber, a double beat valve mounted in said valve chamber and adapted to be alternately moved against 115 said upper and lower seats, said uppermost layer having a passage communicating at one end with said valve chamber and opening at its other end through the side wall of said unit, said passage adapted to register 120 with the second mentioned opening in said wind trunk, said lowermost layer having a passage therein communicating with the central recess in said layer at one end and having its other end opening through the 125 130

side of said unit, said last named passage adapted to register with the first mentioned opening in said wind trunk, a diaphragm beneath said last mentioned recess and 5 adapted to actuate said valve, and means placing said diaphragm in communication with the ducts of a tracker board, substantially as described.

2. In a pneumatic piano action, the combination with a bellows and a wind trunk, of a valve carrying unit removably supported on said bellows and detachably connected to said wind trunk, said valve carrying unit having a valve chamber therein normally 10 in communication with the atmosphere and constantly in communication with said bellows, said unit having a recess below said valve chamber in communication with the exhaust space of said wind trunk, a double 15 beat valve adapted to close the communica- 20

cation of the atmosphere with said valve chamber and to place said recess in communication with the bellows, a diaphragm below said valve and recess and adapted to actuate the valve, an air receiving chamber 25 below said diaphragm, a passage leading from said chamber to the outside of said unit, a second passage above said first named passage opening at one end into said recess and at its other end opening at one side 30 of said unit, a plate fitted up against the side of said unit and having a central boss communicating interiorly with both of said passages, and means for placing the interior of said boss in communication with one of 35 the ducts of the tracker board, substantially as described.

In testimony whereof I affix my signature.

ARCHIBALD EATON GOLDSPINK.
